BODY VIBRATOR

Robert R. Gonsett, Los Angeles, Calif.

Application June 25, 1932, Serial No. 619,194

10 Claims. (Cl. 128—63)

My present invention relates to body vibrators, and the objects of this invention are: first, to provide a vibrator of this class whereby any portion of the human body may be stimulated or vibrated to varying degrees of intensity, and at places normally inaccessible with other devices; second, to provide a device of this class whereby very large portions of the human body may be stimulated, agitated or vibrated with varying degrees of intensity; third, to provide a vibrator of this class which is extremely compact of construction, one which may be readily transported from place to place, one which may be readily supported for operative use, and one which is very neat in appearance; fourth, to provide a device of this class whereby a looped body strap is vibrated by a single electromagnetic means; fifth, to provide a device of this class whereby a looped body strap is secured at its ends to a single reciprocating armature actuated by electromagnetic means, and in which the opposite ends of the strap are connected to opposite ends of the armature, and to that extent, the opposite ends of the strap are independently actuated; sixth, to provide a device of this class in which different portions of the armature are actuated by a unitary electromagnetic means, but which may be differently controlled thereby depending upon the exterior force applied to the different portions; seventh, to provide a novelly constructed armature and novel mounting thereof with respect to the electromagnetic means; eighth, to provide as a whole a novelly constructed body vibrator; and, ninth, to provide a device of this class which is particularly simple and economical of construction proportionate to its functions, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawing and to the characters of reference thereon which form a part of this application in which:

Figure 1 is a perspective view of my body vibrator showing the same suspended as when in use and showing a fragmentary portion of the body strap connected thereto; Fig. 2 is a side view thereof showing certain parts and portions thereof broken away and in section to facilitate the illustration; Figs. 3 and 4 are, respectively, transverse sectional views thereof taken through 3—3 and 4—4 of Fig. 2; and, Fig. 5 is a fragmentary perspective view showing the mounting of the armature and the relation thereof to the electromagnet.

Like characters of reference refer to similar

parts and portions throughout the views of the drawing.

The operating portion of my device consists of an electromagnet A and an armature B. These are encased in a casing 1 having a removable cover 1a at the normally lower or outer end. The casing 1 is tubular being flattened with the flat sides connected by rounded or semi-cylindrical portions.

To the inner side of the cover 1a is secured the connecting strap 2a of a U-shaped supporting member 2, the legs 2b thereof extending inwardly through and immediately adjacent the walls of the semi-cylindrical portions of the casing 1 and through the head 1b at the end of the casing opposite the cover 1a. The supporting member 2 may be secured within the casing 1 in any suitable manner. In this instance, the ends of the legs 2b extending through the head 1b are provided with pairs of transverse slots 2c through which extend the ends of a flexible handle strap 3. The ends of the handle strap engage the outer side of the head 1b and thus hold the legs of the supporting member 2 in position. This handle strap 3 is adapted for carrying the device, as well as for supporting the same on a hook C, as shown in Fig. 1, when using the device.

The electromagnet and the armature are both supported on the legs 2b, the former fixedly, and the latter reciprocally. The electromagnet consists of a laminated core 4 and a coil 5. The core 4 consists essentially of a double horseshoe core with one of the legs of each forming a central wide core portion 4a on which the coil 5 is wound, no coils being wound on the legs 4b at the outer and opposite sides of the coil. The central laminations of the legs 4b are slightly wider and are extended through longitudinal slots 2d in the legs of the supporting member 2 for supporting the electromagnet upon the supporting member 2, the laminations extending through the legs 2b being preferably riveted over, as shown in Figs. 3 and 5.

The armature B is also built up of laminations of considerable width which extend the full length between the legs 2b of the supporting member 2 and are reciprocally mounted thereon. At the opposite sides of the laminations are secured plates or strips of fiber 7 which engage the opposite narrow edges of the legs 2b of the member 2. At the outer sides of the fiber strips 7 are placed rigid plates 8, preferably other metal laminations. All of these plates are secured together as a unitary armature by means of rivets 9. This armature is prevented from engaging the adjacent ends of the core 4, when the electromagnet is electrified by bumpers 10 which extend over the ends of the legs 4b of the core and

are secured at their ends between the outer laminations of the core, as shown best in Fig. 5.

To the armature are secured a pair of hooks 11 which are positioned with their hook portions 11a outside of the casing and which extend with their shank portions 11b through the cover, the connecting strap 2a and into the side of the armature opposite the electromagnet. It will be noted that the hooks are secured to the armature 10 at substantially the opposite ends thereof so that they are substantially independent, that is, when greater force is exerted on one hook than on the other, greater vibrating force is also exerted thereon until the same is drawn beyond its 15 effective limits. The armature is normally forced toward or against the core of the electromagnet by coil springs 12 which, in this instance, are shown positioned around the shanks of the hooks and between the armature and the inner side of 20 the strap 2a of the supporting member 2. These coil springs counteract to some extent the manual force applied in withdrawing the armature from the electromagnet and normally tend to 25 keep the armature in close operative relation with the electromagnet.

The vibration of the device may be imparted to the human anatomy in a number of different ways. The one here shown consists of a flexible band or strap 13 which is of sufficient length to 30 extend around any member or portion of the human body and is secured at its ends in any suitable manner to the hooks 11, as shown.

Though I have shown and described a particular construction, combination and arrangement 35 of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a body vibrator, a casing, an electromagnet mounted therein, an armature reciprocally mounted within the casing and provided at its opposite ends with vibrating arms extending through the end of the casing at the opposite sides thereof, and body contact means connected 45 to said arms.

2. In a body vibrator, a casing, an electromagnet mounted therein, an armature reciprocally mounted within the casing and provided at its opposite ends with vibrating arms extending through the end of the casing at the opposite sides thereof, and a body vibrating strap secured at its opposite ends to each of said arms.

3. In a body vibrator, a casing, an electromagnet mounted therein, an armature reciprocally mounted within the casing and provided at its opposite ends with vibrating arms extending through the end of the casing at the opposite sides thereof, body contact means connected to said arms, and compression springs within the casing 60 between the head and the armature for normally forcing the latter toward the electromagnet.

4. In a body vibrator, a casing, an electromagnet mounted therein, an armature reciprocally mounted within the casing and provided at its opposite ends with vibrating arms extending through the end of the casing at the opposite sides thereof, body contact means connected to said arms, and compression springs positioned around 65 each of the arms and between the end of the

casing and the armature for normally forcing the latter toward said electromagnet.

5. In a body vibrator, a casing, an electromagnet mounted therein, an armature reciprocally mounted within the casing and provided at its opposite ends with vibrating arms extending through the end of the casing at the opposite sides thereof, body contact means connected to said arms, and a supporting strap connected to the end of the casing opposite the end through which said arms extend, the latter strap being adapted for suspending the vibrator. 80

6. In a body vibrator, a relatively flat casing, a removable cover for one end of the casing, said cover having inwardly extending legs projecting through the opposite end of said casing, a supporting strap extending through the ends of the legs for retaining said legs therein and for suspending said casing, an electromagnet within the casing, an armature within the casing in operative relation to the electromagnet, said armature having means extending therefrom, and a body contact member secured to the last mentioned means. 90

7. In a body vibrator, a relatively flat casing, a removable cover for one end of the casing, said cover having inwardly extending legs projecting through the opposite end of said casing, a supporting strap extending through the ends of the legs for retaining said legs therein and for suspending said casing, an electromagnet mounted 100 on said legs at the inner end of the casing, an armature reciprocally mounted on said legs between the electromagnet and said cover and provided with arms extending through said cover, and a body contact member connected to said arms. 110

8. In a body vibrator, a relatively flat casing, a removable cover for one end of the casing, said cover having inwardly extending legs projecting through the opposite end of said casing, a supporting strap extending through the ends of the legs for retaining said legs therein and for suspending said casing, an electromagnet mounted 115 on said legs at the inner end of the casing, and armature reciprocally mounted on said legs between the electromagnet and said cover and provided with hooks at its opposite ends and extending through said cover, and a body vibrating strap secured at its ends to said hooks.

9. In a body vibrator, a relatively flat casing, a removable cover for one end of the casing, said cover having inwardly extending legs projecting through the opposite end of said casing, a supporting strap extending through the ends of the legs for retaining said legs therein and for suspending said casing, an electromagnet mounted 125 on said legs at the inner end of the casing, an armature reciprocally mounted on said legs between the electromagnet and said cover and provided with arms extending through said cover, a body contact member connected to said arms, and compression springs positioned around said arms between the armature and said cover. 130

10. In a body vibrator, a supporting means, an electromagnet mounted at one end of said means and provided with a core extended to the opposite sides of said means, a long armature reciprocally mounted on said supporting means and adapted to be attracted at its opposite ends by the extended portions of the core, resilient means 140 normally forcing the opposite ends of said armature toward said electromagnet, and means connected to the opposite ends of said armature for withdrawing the same from the electromagnet. 145
